ALFREDO MARONE, OF SANTA VITTORIA D'ALBA, ITALY

DEVICE FOR FILLING CONTAINERS WITH LIQUIDS

Application filed November 5, 1931, Serial No. 573,187, and in Italy November 18, 1930.

This invention relates to a device for filling containers with liquids having the characteristic feature that the filling operation is automatically interrupted when the liquid reaches the desired predetermined level in the container.

The means for automatically interrupting the filling process consists of a valve pressed by a spring tending to bring it into its closed position on its seat and held raised therefrom by a device which is caused to act on the valve for effecting the filling operation and is automatically released so as to permit a ready closure of the valve as soon as the liquid in the container has reached a level such that the liquid stream flowing through the conduit of the apparatus produces, according to Venturi's principle, an air suction in a chamber having a movable wall (such as bellows, cylinder and piston, a barometric box or a plurality thereof or the like) the movement whereof causes the valve stop member to be released.

According to this invention, the air suction may be produced by an injector of the usual type effecting a constant suction of the air or gas during the flow of the liquid, which will not give raise to any difficulty when the liquid to be filled into the container does not produce foam, as in the case of water, oil etc. As long as the predetermined level is not reached, the air suction is effected through an orifice communicating with the outside and therefore it does not affect the movable wall of the above mentioned chamber, while the underpressure moves said wall and therefore releases the valve as soon as the liquid reaches and covers the orifice, the density of the liquid being much higher than that of the air sucked in. The orifice will be located at the height at which the filling of liquid into container should be stopped, i. e. at the desired level.

When the liquid to be filled into the container is emulsifiable or apt to form foam, the injector will be caused to come into action for effecting the air suction only when the predetermined liquid level is about to be reached. In this case I employ special means for preventing any contact of the liquid

stream with the wall of the terminal portion of the conduit connected through a suitable pipe with the chamber having a movable wall which releases the stop member holding the valve in its open position. The underpressure in this terminal section of the conduit and therefore also in the chamber having the movable wall is generated only when the liquid in the container reaches the outlet of the apparatus, as the liquid stream then fills the terminal section of the conduit, expelling the air therefrom. The device works henceforth as injector, absorbing air, and the underpressure generated in the chamber causes the valve to be released, filling being thus automatically stopped.

The accompanying drawing shows diagrammatically by way of example two constructions of my apparatus.

Figure 1 is a diagrammatical axial section of the first construction, more particularly for foamy liquids.

Figure 2 shows on an enlarged scale a detail of a construction of the chamber having a movable wall.

Referring to Figures 1 and 2, 1 denotes the body of the apparatus provided with a liquid inlet 2 and an outlet 3 for the liquid streaming into the container, as well as with a valve 4 of which the spindle 5 is fixedly connected with a steep-pitched screw 6 pressed by a torque spring 8 tending always to bring the valve 4 on its seat for throttling the liquid flow through an axial displacement and rotation of said screw. The end of the screw 6 carries fixed thereto a lever 10 provided with a handle 11 which undergoes the same angular movements and translation as the screw 6 and valve 4. The lever 10 is brought by a hand operation to the position shown in Figure 1 and is engaged and retained by the hooked end 12 of a lever 13 pivoted at a fixed point 14, the other end whereof is connected at 15 with the movable wall 16 of a chamber 17, the wall 18 whereof opposite to the wall 16 is fixed. The chamber is closed on its remaining portion by rubber bellows 19 tending to remain open and closing only when an underpressure is generated within the chamber 17. 20 denotes the hose connecting the inside

- of the chamber 17 with a portion of the conduit near the outlet 3 and directly below the conical section 3₁. The conical section 3₁ throttles the liquid stream which is thereby prevented from coming into contact with the walls of the conduit on all the length extending from the point 21 where the hose 20 is connected with the conduit and the outlet 3. A wire jet-breaker is arranged in the conical section 3₁ for regulating the jet issuing from the valve 4 and preventing whirling motions and other disturbances as might cause the liquid stream to contact with the underlying wall before the proper moment.
- 15 In these conditions it is obvious that during the flow of the liquid no air suction can take place in the section of the conduit extending between the point 21 and the outlet 3 until the level of the liquid in the container has reached the outlet 3, when the liquid is compelled to contact with the walls of the conduit. This immediately causes an air suction to be effected and a partial vacuum to be generated in the chamber 17, of which the movable wall 16 is brought near the wall 18, while the lever 13 rocks about the pivot 14 releasing the lever 10 and therefore the spring 8 which closes immediately the valve 4 on its seat stopping the flow of liquid.
- 20 The level control may be operated at any desired liquid level by varying the depth to which the spout end 3 is inserted into the container to be filled, which may be a barrel or any other kind of receptacle.
- 25 It will be understood that the constructional details of my invention may be varied, from the construction of the specific examples described, within the scope of the appended claims, without departing from the spirit of the invention.
- 30 What I claim is:
1. An apparatus for filling a container with a liquid, comprising a conduit with an enlarged outlet for the liquid, a valve in said conduit having a spindle with a steep-pitched screw thread, a cap on which said spindle is screwed, a torque spring tending to rotate said valve to its closed position, an arm secured to said spindle for bringing the valve by hand into its closed position, a retaining lever co-operating with said arm for holding said valve open, a closed box communicating with the enlarged outlet end of said conduit and having a movable wall co-operating with said retaining lever and means for keeping the liquid stream away from the wall of said outlet end, so that when the level of the liquid in the container rises and closes the opening of said outlet end an underpressure is generated in said chamber for moving said movable wall so as to release said valve from said retaining means.
- 40 2. A device for filling containers with liquids and having means for automatically interrupting the flow of the liquid at the de-
- sired level, comprising, in combination with a valve, spring means tending to bring said valve into the closed position, retaining means for holding said valve in its open position and a member operated by pressure for releasing said valve from the retaining means, a spout end, a jet-breaker in said spout end for producing a steady liquid column descending vertically from said spout end, an enlarged tubular extension of the spout end surrounding and spaced from said liquid column at its issue from the jet breaker, and a conduit placing the interior of said tubular extension in communication with said member operated by pressure.
- 45 3. A device for filling containers with liquids and having means for automatically cutting off the flow of the liquid at a predetermined level comprising, in combination, a conduit for the liquid, a valve in said conduit having a stem with a steep-pitched screw thread, a cap on which said stem is screwed, a torque spring tending to rotate said valve to its closed position, an arm secured to said stem adapted to bring the valve manually into its open position, a retaining lever co-operating with said arm for holding said valve open, a member actuated by pressure operatively connected with said arm to release it from said retaining lever when the pressure is reduced under a predetermined value, a spout end, a jet breaker in said spout end to produce a steady column of liquid descending vertically from said spout end, an enlarged tubular extension of the spout end surrounding said liquid column at its issue from the jet-breaker, and a conduit placing the interior of said tubular extension in communication with said pressure actuated member.
- 50 In testimony whereof, I hereunto affix my signature.
- 55 ALFREDO MARONE.
